UNITED STATES PATENT OFFICE.

MORTIMER NORDEN, OF NEW YORK, N. Y., ASSIGNOR TO JOSEPH NORDEN, OF NEW YORK, N. Y.

COMBINED ATTACHMENT PLUG AND BASE.

1,151,214.

Specification of Letters Patent. Patented Aug. 24, 1915.

Application filed November 7, 1913. Serial No. 799,659.

To all whom it may concern:

Be it known that I, MORTIMER NORDEN, a citizen of the United States, residing at the borough of Manhattan, in the city, county, and State of New York, have invented an Improvement in Combined Attachment Plugs and Bases, of which the following is a specification.

My invention relates to a combined electrical attachment plug and base, and its object is to provide means for connecting an extension or branch at any desired place in an electric main.

The details and operation of the invention are hereinafter particularly described.

In the accompanying drawing Figure 1 is an elevation of my combined attachment plug and base connected together. Fig. 2 is a plan view of the same, in which the main conductor wires are shown in broken lines. Fig. 3 is a vertical section on the line *xx* of Fig. 2, showing the plug and base attached to a connection box, and Fig. 4 shows in vertical section a modified form of connecting the branch wires with the plug.

Similar reference numerals indicate like parts throughout the several views.

The plug 1 and its base 2 are both made of porcelain or other insulating material. The base 2 is preferably of circular formation, having an integral flange 3, and a central opening 4 with oppositely disposed recesses 5 for the reception of the plug 1 and its contact pieces.

6 6 are lugs of insulating material, preferably made integral with the base, one of which lugs projects in line with the side wall of one of the recesses 5 at its right hand side, while the other lug projects in line with the other recess 5 at its left hand side.

7 7 are spring contact clips of metal located upon the top surface of the base 2, which clips are curved to conform to the shape of the base and the central opening therein. The free ends of these spring contact clips 7 are bent slightly upward for the purpose hereafter described. 8 8 are metallic contact plates arranged adjacent to the respective lugs 6, and placed over and in contact with one end of each of the said spring contact clips 7. Screws 9 pass through holes in the base and clips and screw into screw threaded holes in the plates 8.

10 10 are metallic binding screws screwing into screw threaded openings in the plates 8 and through openings in the clips 7 and into screw threaded openings in the base. These binding screws 10 are for holding the main line wires 11 to the plates 8 on the base 2, the insulating material being removed from said wires a short distance to allow the bared portions of the wires to be looped around the binding screws 10 under their heads, so that when the screws are forced down to place the main wires are brought into intimate contact with the plates; one end of each plate 8 is upturned to assist in holding the bared line wires in position. The flange 3 of the base is provided with screw holes 12 for the attachment of the base to a connection box 13, or other foundation by screws 14.

The plug 1 has a neck or portion of reduced diameter 15 adapted to enter and fill the central opening 4, in the base 2. There is a central opening 16 extending entirely through the plug 1 through which pass the branch conductor wires 17. On the opposite sides of this central opening in the plug, there are recesses 18 of a depth approximately half the length of the plug. In each of these recesses 18 there is inserted a metal rod 19 of a length and diameter to entirely fill and close such recesses. The ends of these rods 19 project slightly outside the recesses 18 at the top of the plug and are provided with integral contact pieces 20, which extend at right angles a predetermined distance beyond the outer surface of the neck of the plug.

The metal rods 19 are firmly secured within the recesses 18 by the set screws 21 which pass through holes in the sides of the plug and into screw-threaded holes in the rods. The heads of such screws being countersunk in the neck of the plug. In the upper end of each rod 19 there is a screw-threaded hole to receive the binding screws 22.

The insulating material is removed from the ends of the branch conductor wires 17 projecting beyond the top of the plug 1, and the bared wires are twisted around the binding screws 22, which are then screwed down so that intimate contact is made with the right angled contact pieces 20 of the rods 19.

In connecting the plug 1 with the base 2, the right angled contact pieces 20 are

brought in line with the recesses 5 in the base and the neck 15 of the plug is then pressed into the central opening 4 in the base, (the contact pieces 20 at the same time 5 passing into the recesses 5), until that portion of the plug having the larger diameter comes into contact with the bottom of the base and prevents the further entrance of the plug 1, and in this position the right angled contact pieces 20 have passed entirely through and out of the recesses 5 and their under surfaces are but slightly raised from the top surface of the base. Now by giving the plug a half rotation to the right, the contact pieces 20 will pass under the spring contact clips 7 and remain in intimate frictional contact therewith, thus forming both mechanical and electrical connection between the plug and its base. The bent up ends 20 of the clips 7 assuring the free passage of the contact pieces 20 beneath the clips. It will be seen that the lugs 6 prevent the plug 1 being rotated in the wrong direction.

In Fig. 3 of the drawing I have illustrated the device as attached to a connection box, but it is obvious that the base may be secured to any suitable support.

While I prefer to connect the branch wires 17, with the plug in the manner shown in Figs. 1, 2 and 3, and as above described, they may be connected in the manner shown in Fig. 4, whereby the central opening in the plug, and the binding screws 22 are dispensed with. In such case, instead of the recesses 18 the bores are extended entirely through the plug leaving two spaced apart longitudinal openings 23, into which the rods 19 are inserted and clamped in the same manner as above described, but each rod 10 has a central longitudinal bore 24 and the branch conductor wires 17 are inserted into the openings 23 in the plug, the insulation being removed from their ends, which bared ends are inserted into the bores 24 in the rods 19, the set screws 21 serving also to clamp these bared ends of the branch wires therein.

I claim as my invention:

1. A plug of insulating material provided with two spaced elongated recesses longitudinally disposed, metallic rods filling said recesses and projecting therefrom at the top at right angles to the plug in opposite directions, branch wires connected with said metallic rods, in combination with a base of insulating material having openings for the passage of said plug and right angled projections, contact plates for connection with an electric main secured to said base, metallic spring clips in contact with said plates and secured to the base and positioned to overlie and contact with said right angled projections on a partial rotation of the plug and secure said projections between the clips and base. 65

2. A plug of insulating material provided with two spaced elongated recesses longitudinally disposed, metallic rods within said recesses and projecting therefrom at the top at right angles to the plug in opposite directions, branch wires connected with said metallic rods, in combination with a base of insulating material having a central opening with a recess on two opposite sides thereof for the passage of said plug and right angled projections, a lug projecting from said base in line with the right side wall of one of said recesses, another lug projecting from said base in line with the left side wall of the other recess, contact plates for connection with an electric main secured to said base, metallic spring clips in contact with said plates and secured to the base in a position to overlie and contact with said right angled projections on a partial rotation of the plug 80 and secure said projection between the clips and base. 75

Signed by me this 25th day of October 1913.

MORTIMER NORDEN.
